UNITED STATES PATENT OFFICE.

GEORGIA LORENA PENNY, OF ALLSTON, MASSACHUSETTS.

FILM-CARRYING DEVICE.

1,325,372.

Specification of Letters Patent. Patented Dec. 16, 1919.

Application filed February 26, 1918, Serial No. 219,271. Renewed June 12, 1919. Serial No. 303,771.

To all whom it may concern:

Be it known that I, GEORGIA LORENA PENNY, a citizen of the United States, residing at Allston, in the county of Suffolk and State of Massachusetts, have invented certain new and useful Improvements in Film-Carrying Devices, of which the following is a specification:

This invention relates to film carrying devices especially adapted to be secured to a camera carrying case and has for its object the production of a simple and efficient film carrying device which may be attached to the ordinary camera carrying case.

Another object of this invention is the production of a simple and efficient film carrying receptacle which may be secured to the ordinary camera carrying case and which will be held firmly in engagement with the sides thereof and prevented from slipping longitudinally upon the carrying strap.

Other objects and advantages of the present invention will appear throughout the following specification and claim.

In the drawings:

Figure 1 is a front elevation of a camera carrying case, showing the film carrying receptacles secured thereto,

Fig. 2 is a side elevation of one of the film carrying receptacles,

Fig. 3 is a vertical section through a portion of a camera carrying case showing the film carrying receptacle also in section,

Fig. 4 is a section taken on line 4—4 of Fig. 3.

Fig. 5 is a section taken on line 5—5 of Fig. 4.

By referring to the drawings, it will be seen that 1 designates the camera carrying receptacle which is provided with the usual carrying straps 2, these carrying straps 2 being secured at their lower end as indicated at 3, at a point intermediate the ends 45 of the camera carrying case 1.

A film carrying receptacle 4 is adapted to fit upon each side of the camera carrying receptacle 1 as shown in Fig. 1 of the drawings, and each film carrying receptacle 4 comprises a flat back strip 5, and an outer bulged front strip 6, the front strip 6 being secured along the side edges as indicated at 7 through the rear strips 5 as shown clearly in Fig. 4 of the drawings.

55 A cover flap 8 is secured to the rear strip 5 and overhangs the upper end of the re-

ceptacle 4 as shown in Fig. 1 of the drawings, and this closure flap 8 is provided with a fastener 9, this fastener 9 being adapted to engage the fastener 10 carried by the receptacle 4.

The rear strip 5 is provided with a strap receiving aperture 11 formed intermediate the ends thereof and preferably located near the center of the film supporting receptacle 4 as shown in Fig. 4 of the drawings. The carrying strap 2 is adapted to be extended through the aperture 7 and lie snugly upon the inner face of the strips 5 as shown in Fig. 3, this carrying strap 2 also passing through an aperture 12 formed in the cover flap 8 as shown in Figs. 3 and 4 of the drawings. It should be understood that owing to the passing of the strap 2 through the aperture 11 in the manner illustrated in Fig. 3, and above 75 described, the receptacle 4 will be firmly held in engagement with the camera carrying case 1 and held against longitudinal slipping upon the strap 2 due to the frictional gripping, which is caused by passing the strap 2 through the aperture 11 and causing the strap 2 to engage the outer face of the strips 5 near the lower end thereof and the inner face of the strips 5 near the upper end thereof. In this way, the receptacle 4 will be held against unnecessary longitudinal slipping movement upon the supporting or carrying strap 2. As shown in Figs. 1 and 3, the receptacles 4 are preferably or approximately the same height as the camera carrying receptacle 1 and are approximately twice as long as the width of the receptacle 1 for the purpose of permitting two films to be carried upon each receptacle. As shown in Fig. 1, a receptacle 4 is adapted to be carried upon each side of the camera carrying case 1 for the purpose of firmly holding the film in a stored condition while not in use, in this way making an accommodation for four films.

100 What is claimed is:

A combined camera casing and film carrying receptacle comprising a camera carrying casing, a carrying strap having its ends secured firmly to the sides of said camera carrying casing at a point intermediate the upper and lower ends thereof, a film carrying receptacle provided with slots formed upon the inner face thereof intermediate the upper and lower ends of the film carrying receptacle, said carrying strap passing down against the inner face of the

inner wall of said film carrying receptacle and threaded through said aperture, for detachably securing said film carrying receptacle to said camera carrying casing, the lower end of said film carrying receptacle fitting snugly against the side wall of said camera carrying casing and said carrying strap adapted to normally hold the film

carrying receptacle in vertical relation with respect to said camera carrying casing. 10

In testimony whereof I affix my signature in presence of two witnesses.

GEORGIA LORENA PENNY.
